[57] **CLAIM**

The ornamental design for a holder for fixedly retaining toy templates, substantially as shown and described.

DESCRIPTION

FIG. 1 is a top, left and front perspective view of a holder for fixedly retaining toy templates showing my new design in a closed position;
FIG. 2 is a rear elevational view;
FIG. 3 is a right side elevational view;
FIG. 4 is a bottom plan view; and
FIG. 5 is an exploded perspective view in an opened position with the drawer removed.
